QUINIDINE POLYMANURONATE

The quinidine base is a well-known alkaloid, stereoisomer of quinine, in whose nucleus of quinuclidine a methyl group is found.

The cardio-dynamic and anti-arrhythmic properties of this alkaloid are known, but its oral administration in the form of conventional inorganic salts of the quinidine base presents the disadvantage of producing certain disturbances. It is generally recognized that the gastro-intestinal disturbances that appear after the use of conventional compounds of quinidine are due, in the majority of cases, to a local irritation more than to a systemic toxic manifestation. It is believed that this irritation is due to the ionic shock that is produced in the gastro-intestinal mucosa as a consequence of the liberation by rapid dissociation of the irritant ions of the conventional inorganic salts of the quinidine base.

The solutions proposed up to now to palliate these disadvantages have proved to be insufficient. Among the methods that have been suggested to prevent this undesirable effect are the diminution of the dose, which supposes a diminution of the therapeutic effect; the utilization of parenteral injection, which is troublesome in the case of prolonged treatments; special enteric coverings of the tablets, which protect the stomach but not the intestine, or the addition of substances which protect the gastric and intestinal mucosa, such as anti-acids or neutralizers.

The purpose of this invention is to reduce the undesirable effects mentioned, without reducing the therapeutic effect or having recourse to troublesome forms of administration.

These and other advantages which will appear in the description that follows are achieved by means of the provision of a quinidine salt with polymanuronic acid, which salt is not very soluble and has a very low and constant index of dissociation.

Quinidine has proved to be efficacious in patients suffering from arrhythmic cardiac affections resisting treatment through other alkaloids derived from quinidine, such as, for instance, dihydroquinidine or quinine.

The polymanuronic acid, which is not dissolved or absorbed in the stomach, becomes slowly dissolved in the intestinal tract. It is endowed with emollient properties, and increases its volume several times in contact with humidity, for which reason it acts as a protector of the digestive mucosa, forming a film over the latter and preventing local irritation.

On the other hand, the fact of a slower dissociation of the salt in polymanuronic acid and quinidine provides a more uniform intestinal absorption, with more stable and lasting hematic levels of quinidine. This gives it a kind of effect similar to that of "depot" ad-

ministration, which undoubtedly facilitates its administration and makes more comfortable its dosage in the case of patients who habitually should have to take various doses repeated throughout the day and the night.

5 Polymanuronic acid is formed by long polymer chains of manuronic acid cycled in pyranosic form in such a manner that its carboxyl groups remain free.

20 It is a relatively strong polyacid, capable of decomposing carbonates, and which can form inorganic and organic salts as well as esters. The length of its chain depends on the processes employed in its extraction and purification from certain classes of algae which contain it, and on the resultant hydrolysis that it undergoes, its molecular weight being, in general, of the order of 240,000, and so it proves to be formed by some 1360 monomer units of manuronic acid.

25 30 It is not soluble in water, but on making contact with the latter it swells absorbing from 200 to 300 times its weight in water and forming a gel. This gel is not attacked by the gastric juice and dissolves slowly in the alkaline medium of the intestine.

35 In the reaction of polymanuronic acid with the quinidine a yellowish odourless powder with a bitter taste is obtained, which decomposes at 180°C, and which proves to be insoluble in common solvents, except aqueous methanol and ethanol and propylene glycol.

40 45 The empirical formula of the quinidine polymanuronate is $(C_{26}H_{32}O_8N_2)_x$, the value of x depending on the number of monomer units existing in the chain of the acid. The compound presents a content of 60.46% of quinidine.

50 55 The infrared spectrum results characteristic and can be compared with that of the stoichiometric mixture of quinidine and polymanuronic acid, FIGS. 1, with the compound, FIG. 2, the existence of the latter being demonstrated by the peak that is found at 1615 cm^{-1} corresponding to carboxylates and the disappearance of the peak corresponding to carboxyls and which appears as a broader band towards 1710 cm^{-1} as well as by its solubility.

Quinidine is soluble in methanol, in ethanol of 96°, chloroform, propylene glycol, acetone, etc. Polymanuronic acid is insoluble in these solvents, is only very slightly soluble in water, and is soluble in solutions of alkalis and/or carbonates. The compound is insoluble in methanol, ethanol of 96°, chloroform, cold propylene glycol, acetone, etc., being soluble in methanol and/or ethanol at 50 per cent and in hot propylene glycol.

60 65 A simple mechanical mixture of polymanuronic acid and quinidine will consequently partially dissolve the quinidine in one of these solvents, while the compound will remain insoluble.

A mechanical mixture of polymanuronic acid and quinidine melts between 112° and 117°C. At this same

temperature the polymanuronic acid begins to darken. At 170°C the quinidine melts. At 180°C the acid ceases to darken, and the compound, which becomes totally decomposed at 190°C, commences to darken.

The rotatory power of $(C_{26}H_{32}O_8N_2)_x$ is: +77.3° (Propylene glycol, $c = 0.5$).

The preparation of quinidine polymanuronate should be begun with an evaluation of the polymanuronic acid to establish its chemical equivalent and to know the proportion of quinidine with which it will react. The course of the reaction can be followed, in addition to observing the change of aspect of the reacting mixture, by the pH values which, on the termination of the reaction, will be practically neutral. The compound is separated by filtration and is purified by means of repeated extractive washings. Finally, the product presents the aspect of a fine dry powder, of slightly yellowish colour, stable in air at ambient temperature and up to some 150°C.

The reaction between the polymanuronic acid and the quinidine can be brought about when both compounds are found in a free state, or by means of a double decomposition between a metal salt of the polymanuronic acid and an appropriate organic and inorganic salt of the quinidine.

Once the polymanuronic acid has been valued and the stoichiometric equivalent of quinidine has been calculated, the product can be obtained in the following manner:

Polymanuronic acid is suspended in a hydroalcoholic solvent, and to this suspension there is added, while stirring, an equal volume of the same solvent containing the necessary quantity of quinidine. The mixture is kept at a moderate temperature and is agitated until the reaction finalizes. It is then rapidly cooled and filtered. By evaporating the solvent in vacuum and at the lowest possible temperature, new quantities of the compound are recovered. The dry residue is washed with absolute ethanol, is filtered and is again dried.

Once the reaction has terminated, the product may also be isolated by concentrating it in vacuum until it forms a paste. Then a double volume of acetone is added, it is cooled, it is left in repose for 24 hours, it is filtered and the product is dried.

Alternatively, it is suspended in water and polymanuronic acid, and to this suspension, which is heated and stirred, there is added an equal volume of a solution of the quinidine necessary in an alcohol of low molecular weight. The separation of the product is effected by any of the three processes given above.

Again, the polymanuronic acid can be previously dissolved in the necessary quantity of sodium hydroxide 0,1 N or in another hydroxide, carbonate or bicarbonate of alkaline or alkaline-earth metal.

Instead of the quinidine in its basic form, one of its salts may be employed with an acid such as sulphuric, hydrochloric, hydrobromic or nitric.

For any process that is followed for obtaining quinidine polymanuronate, the beginning consists of an evaluation of the polymanuronic acid by suspending in water 0.500 grams of the latter and titrating with sodium hydroxide 0,1 N, employing phenolphthalein as an indicator.

From this evaluation there is deduced the stoichiometric equivalent of quinidine for a given quantity of the acid. In the experiment carried out the equivalence was 10.0 grams of polymanuronic acid for 15.8 grams

of quinidine, and with these quantities the obtention tests were carried out.

EXAMPLE 1

5 10 grams of polymanuronic acid are suspended in 400 ml of methanol at 50 per cent v/v and, by means of a funnel fitted with a tap, it is slowly added (the time taken being from one to one and a half hours) to a suspension of 15.8 grams of quinidine in another 400 ml of the same solvent contained in a 2 litre matrass with reflux refrigerant, and mechanical agitation keeping it in a water bath at 70° - 75°C.

10 The process of reaction, in all cases, should last for a minimum of 2 hours, more than three hours not being necessary.

15 Once the reaction has been completed, the matrass is cooled in a bath of crushed ice mixed with sodium chloride to give a temperature of at least -10°C (a refrigerated chamber may also be employed). At the end of some 6 hours it is rapidly filtered by means of a Buchner funnel and the product is dried at a temperature below 110°C.

20 The filtered solvent can be employed in a new obtention process, or can be evaporated by means of a vacuum at a temperature not exceeding 60°C, thus recovering a new portion of the product.

25 The dry residue is washed with absolute ethanol, is filtered and is again dried.

EXAMPLE 2

30 In a 2 litre matrass with mechanical agitation and reflux refrigerant, 10 grams of polymanuronic acid and 400 ml of water are placed. The matrass is heated in a water bath up to 70° - 75°C, and there is slowly added, by means of a funnel fitted with a tap, 15.8 grams of quinidine in 400 ml methanol or of ethanol of 96°. As in the case of the previous example, the reaction will be completed in less than three hours.

35 The reaction mixture is distilled until it reaches the consistency of a paste at a temperature between 50° and 60°C and a pressure of 40 to 60 mm of mercury. To the residual paste there is added, in cold, a volume of acetone that is approximately double. The mixture is left overnight in repose in a refrigerator which maintains it below 5°C, it is filtered and the product is dried.

EXAMPLE 3

40 Instead of free polymanuronic acid and quinidine which is also free, there may be employed one of the sodium, potassium, ammonium or magnesium salts of polymanuronic acids, and sulphate, nitrate, chlorohydrate or bromohydrate of quinidine, water being employed as a solvent in these cases.

45 The vessel for the reaction, as well as the technique to be followed, are the same as in the foregoing examples.

50 The separation of quinidine polymanuronate can also be effected by means of evaporation of the water and drying of the residue in a centrifuge atomizer at a temperature not exceeding 60°C.

55 The residue is washed with water until the elimination of the corresponding salt that is formed with the cation of the acid and the anion of the quinidine and after drying it is again washed with absolute ethanol or acetone.

60 In all, there are established three processes for obtention and three processes for separation of the product,

it being possible to employ for its production any of the nine combinations possible.

I claim:

1. A process for obtaining a salt of polymanuronic acid and quinidine of the empirical formula $(C_{26}H_{32}O_xN_2)_x$, wherein x is about 1360, which comprises reacting polymanuronic acid or a metal salt thereof with quinidine or its sulphate, hydrochloride, hydrobromate or nitrate salt in stoichiometric amounts at a temperature of between 70°C and 75°C in the presence of a solvent, until the pH of the reaction solution is about 7, and isolating the quinidine polymanuronate thus formed.

2. A process in accordance with claim 1, in which the solvent employed is a hydro-alcoholic solvent and the polymanuronic acid and quinidine are employed in the form of a free acid and a free base, respectively.

3. A process in accordance with claim 1, in which the polymanuronic acid is employed in suspension in water, and the quinidine is added in solution in an equal quantity of an alcohol of low molecular weight.

4. A process in accordance with claim 1, in which the polymanuronic acid is employed in the form of its sodium, potassium, ammonium or magnesium salt.

5. A process in accordance with claim 1, in which in the appropriate quantity of sodium hydroxide 0.1 N sodium hydroxide.

6. A process in accordance with claim 1, in which the quinidine is employed in the form of its salt with sulphuric, hydrochloric, hydrobromic or nitric acid.

7. A process in accordance with claim 1, in which the solvent is a hydro-alcoholic solvent containing from 40 to 60 percent by volume of water and from 40 to 60 percent by volume of an alcohol of up to 4 carbon atoms.

8. A process in accordance with claim 1, in which the isolation of the product salt is effected by cooling the

reaction mixture to below 0°C, filtering and drying the product, washing the product with absolute ethanol, and filtering and drying the resultant product.

9. A process in accordance with claim 8, in which the filtrate resulting from the first filtering step is evaporated in vacuum at a temperature down to -50°C to separate an additional quantity of the product salt.

10. A process in accordance with claim 1, in which the isolation of the product salt is effected by concentrating the reaction mixture in vacuum until a paste is formed therefrom, adding a double volume of acetone to the paste, cooling the resultant mixture, allowing the cooled mixture to stand for 24 hours, and filtering and drying the resultant product.

11. A process in accordance with claim 1, in which the isolation of the product salt is effected by evaporating the solvent in a vacuum atomizer, washing the resultant powdered residue with acetone or absolute ethanol, and filtering and drying the resultant product.

12. A quinidine salt of polymanuronic acid having the following characteristics:

- a. fine powder of yellowish color,
- b. stable in air at from ambient temperature to about 150°C,
- c. empirical formula $(C_{26}H_{32}O_xN_2)_x$, wherein x is about 1360,
- d. quinidine content of about 60.46% by weight,
- e. infrared spectrum indicating a peak at 1615 cm^{-1} , with a broad band at 1710 cm^{-1} ,
- f. soluble in 50% methanol, 50% ethanol and hot propylene glycol, and insoluble in methanol, 96% ethanol, chloroform, cold propylene glycol and acetone,
- g. total decomposition at 190°C,
- h. rotation of $+77.3^\circ$ (propylene glycol, $c=0.5$).
